UNITED STATES PATENT OFFICE.

MARTIN A. HOWELL, JR., OF CHICAGO, ILLINOIS.

FLASK FOR CARBURETING FILES OR OTHER CUTTING-TOOLS.

SPECIFICATION forming part of Letters Patent No. 283,396, dated August 21, 1883.

Application filed March 17, 1883. (No model.)

To all whom it may concern:

Be it known that I, MARTIN A. HOWELL, Jr., a citizen of the United States, residing at Chicago, in the county of Cook and State of Illinois, have invented certain new and useful Improvements in Apparatus for Deoxidating and Carbureting Files and other Cutting-Tools, of which the following is a specification.

This invention relates to the manufacture of cast-iron and steel files, screw-taps, dies, and other cutting-tools.

The accompanying drawing is a longitudinal sectional view of a flask and a plan view of a gas-holder embodying my invention.

It is well known that no bar of steel can be heated and reheated during the forging of file-blanks without more or less oxidation upon its surface and consequent loss of hardening power, which reduces the standard of its quality; and, further, during the annealing process, which is requisite in file-making to soften the metal preparatory to surfacing and cutting, the free carbon is oxidated, thus depriving the metal of its characteristic as a true carbide or carburet, and decreasing its power of resistance when subsequently hardened and tempered.

In order to convert cast-iron into bar-iron, it is necessary to remove the carbon and silicon associated with it. This is done by heating it in contact with oxide of iron, whereby the carbon is evolved in the form of carbonic oxide, while the silicon, also combining with a portion of the oxide, is converted into silieic acid, which unites with another portion, forming a fusible slag which separates from the metal. In white cast-iron, however, the proportion of silicon is only about one per cent. This bar-iron may be again converted into cast-iron by restoring the proper percentage of carbon by cementation. In all the processes heretofore known, however, the metal has been heated in the presence of both carbon and oxygen, the latter being derived from the pressure of atmospheric air. The consequence is that instead of the pure carbon, with which the metal was formerly combined, the known processes of cementation restore to the metal an oxide of carbon, and the presence of oxygen causes an oxidation of the surface of the metal, which, in the process of converting a tool having a cutting edge or edges or cutting-teeth from bar-

iron back to white cast-iron, would entirely defeat the object of my invention by reason of the brittleness of the oxide.

The object of my invention is to avoid the above objections and to provide efficient means for producing files and other cutting-tools of greater durability and tenacity than heretofore, whereby the carbon and metal are both deprived of the injurious effects of oxidation incurred during the steps they must necessarily pass in forging and annealing.

The object of my invention I accomplish in the manner and by the means hereinafter described and claimed, reference being had to the accompanying drawing, in which the figure is a longitudinal sectional view of a flask or retort embodying my invention.

The flask is constructed in the form of a hollow cylinder, number 1, with a permanently-closed end, 2, and at its other end is provided with an annular tapering collar, 3, surrounding its mouth 4. The cover 5 for the flask is constructed with an annular projecting flange, 6, made flaring or tapering on its internal surface to accurately fit over the tapering collar 3, being clamped and firmly held thereon through the medium of a spring-yoke, 7, the arms of which are provided with lugs to engage the rear edge of the collar 3, and a screw, 8, passing through a threaded socket, 9, in the yoke, and bearing at its inner end directly against the cover, all in such manner that the mouth of the flask is sealed to secure the same from leakage of air or the gas with which the flask is to be charged.

In one end of the flask is a pipe or tube, 10, provided with a cock or valve, 11, such pipe or tube preferably passing through the cover, 90 and adapted to connect with a reservoir or gas-holder, 14, containing pure hydrocarbon vapor, or its equivalent, under pressure, and so jointed adjacent to the cock or valve that the pipe can be separated at that point to disconnect the flask from the gas-holder when the flask is removed from the furnace, as herein-after explained. The flask is provided with a vent-tube, 12, preferably passing through the cover and provided with a cock or valve, 100 13.

The flask may be made of wrought or cast iron, but preferably of an alloy consisting of iron and nickel to avoid oxidation of the flask

at a high heat, the relative proportions in which these two metals enter into the alloy being preferably one part of nickel to four or five parts of iron.

5 The file-blanks having been formed by forging and annealing to soften the metal, they are surfaced and cut by any of the well-known methods, and afterward arranged within the flask, which is then placed in a muffle or furnace and connected with the gas-holder. The vent-cock 13 and valve 11 being opened, a current of pure hydrocarbon vapor will pass into the flask and expel all air therefrom through the vent-cock until, by the lighting of the flame at the mouth of the vent-cock, the evidence of the purity of the vapor and its freedom from oxygen is assured, when the vent-cock is closed and the files held in an atmosphere of pure hydrocarbon vapor free from oxygen until a high annealing-heat is reached. The vent-cock is again opened. The pressure is now increased at the reservoir or gas-holder until the operation of deoxidation and carbureting is completed, which, at the proper heat, can be effected in one hour. The flask is then disconnected from the gas-holder, sealed by closing the valve 11, and withdrawn from the muffle and permitted to cool with the contents enveloped in the deoxidating and carbureting vapor, the flask not being opened until the contents are cold.

If the files being treated are made of cast-iron, the metal will be restored to a true carbide or carburet, while if the files are made of steel the metal will be restored to its true character, exhibiting the characteristics of a true carbide or carburet. The files are by the means described brought to a standard of extreme durability, and are hardened and tempered in the usual manner. A file deoxidized and carbureted by the means described can be hardened and tempered at a much higher degree of heat without burning than is possible where the oxidized metal is left, as in the usual annealing process, a simple oxide. I have employed chemical equivalents of hydrocarbon vapor to accomplish the desired object—such as carbonic oxide, carbonate of ammonia, hydrochlorate of ammonia, &c.; but I prefer to use a simple but pure vapor of hydrocarbon.

In the process of annealing cast-iron in the presence of oxides or other matter having an affinity for carbon more or less of the free carbon remains in an oxidized condition. Now, by the final process of conversion in an atmosphere of hydrocarbon vapor by the exclusion of all traces of oxygen the oxidized carbon is

entirely deoxidized, leaving the metal a true carbide of iron—a standard impossible to be reached by any known process in manufacturing steel. Steel, therefore, is not a true carbide, as supposed by scientists, but an oxidized carbide of iron. In an oxidized carbide part of the carbon is combined with the metal and part is crystallized between the particles or fibers, and the latter is generally known as "graphitic carbon." The annealing-heat will oxidize the latter by the admission of air at the point of expansion of the carbon, when the expansion of the carbon disintegrates the particles of metal or expands the metal, by which it becomes porous and admits air under the pressure of the surrounding atmosphere. This instantly oxidizes it and reduces it to graphite or free carbon, which, on breaking, after cooling gradually, is plainly seen in all annealed steel. When the carbon is wholly combined, as in pure white iron or a true carburet, no process of annealing will show any carbon crystallized between the particles of iron. Nor can it be oxidized at a point below fusion, and in many cases until the heat is raised beyond the point of fusion.

The flask, being portable, is readily removed from the furnace or muffle, which is an essential feature, to permit their gradual cooling while sealed to prevent the admission of air, the blanks not being removed until they are cold, up to which time they are surrounded by the vapor of hydrocarbon.

Having thus described my invention, what I claim is—

1. As a means for converting tool-blanks into a pure carburet, a portable flask having a cover hermetically sealing the same, combined with a hydrocarbon-gas holder and means for connecting the flask with and disconnecting it from the gas-holder, substantially as and for the purpose described.
2. The combination of a portable flask adapted to be placed in and removed from a furnace or muffle, and having a cover for hermetically sealing the same, with a hydrocarbon-gas holder, a valved pipe for connecting the flask with and disconnecting it from the gas-holder, and a valved vent-tube, substantially as described.

In testimony whereof I have hereunto set my hand in the presence of two subscribing witnesses.

MARTIN A. HOWELL, JR.
